UNITED STATES PATENT OFFICE.

JOHN J. WARREN, OF BROWNVILLE, NEW YORK.

MACHINE FOR WINDING PAPER.

No. 798,241.

Specification of Letters Patent.

Patented Aug. 29, 1905.

Application filed March 2, 1905. Serial No. 248,099.

To all whom it may concern:

Be it known that I, JOHN J. WARREN, a citizen of the United States, residing at Brownville, in the county of Jefferson and State of New York, have invented certain new and useful Improvements in Machines for Winding Paper, of which the following is a specification.

This invention relates to improvements in machines for winding paper designed for use in connection with paper-making machinery, by which the material is made in continuous lengths and wherein the finished paper is received by the winding-machine and by it reduced to compactly-wound rolls of different sizes suitable for commercial use; and the invention relates particularly to improvements in that class of paper-winding machines shown and described in Letters Patent heretofore issued to myself, numbered and dated as follows: No. 631,513, dated August 22, 1899.

The invention further relates to paper-winders of the class known as "double-drum winders," and particularly to machines employing two winding-drums of unequal size for the purpose of driving or operating a displaceable receiving - core, which during the course of the winding of a roll of paper is constantly kept in operative contact with said winding - drums and in which the smaller drum is driven at a higher rate of speed relatively than the larger drum for the purpose of effecting the uniform, compact, and smooth winding of a roll of paper or like material.

The object of the present invention is to improve the construction and operation of double-drum-winding machines of the class referred to, to provide for greater rapidity, economy, and safety in the operation of such machines, to make certain parts of the device more positive and reliable, and generally to broaden the scope and usefulness of winding-machines of the class.

A prominent feature of this invention as compared with previous devices of the class lies in the substitution of an adjusting-shaft provided with hand - wheels, clutches, and gears in place of the lever, ratchet - wheels, and links formerly employed to increase or decrease the pressure of the receiving - roll upon or against the winding-drums; and the invention further consists in substituting sprocket-wheels and sprocket-chains, the latter being provided with adjustable and flexi-

ble parts in place of the plain cables, roller-guides, and weights shown in former inventions.

Another feature of the present invention consists in providing an apron or carrier comprising a band or web of canvas or other suitable material which is disposed on the under side of the large winding-drum. The object of this apron or carrier is to receive the free end of the paper as it comes from the slitter and to carry it around the under side of the larger drum and thence upward between the two drums, where the operator catches the paper and makes it fast to the core or shaft upon which the paper is to be wound. By reason of this provision the operator is not required to go under the machine, as has been required to be done in former devices of the class, and the work is therefore more readily and safely accomplished by the employment of the said apron.

Other features and parts of the invention will be more readily understood by reference to the drawings forming a part of this specification, and in which—

Figure 1 is an end elevation of the winding-machine embodying my invention. Fig. 2 is a front elevation, partly in section, of the machine with the center portion omitted, showing the apron or carrier and the various adjusting parts. Fig. 3 is an elevation of the upper portion of the winding-machine, showing the receiving core or shaft, supported on the adjustable bearings, mounted on the pivoted guide-rods, and other related parts. Fig. 4 is a vertical end section, substantially on the line *a a* of Fig. 2, showing the manner of applying the apron or carrier to the large drum and showing the ratchet - gear and sprocket-chain tension parts. Fig. 5 is an enlarged sectional view of the adjusting-shaft and coöperative parts, substantially on the line *x x* of Fig. 2. Fig. 6 is an elevation of one of the hand-wheels, showing a portion of the clutch. Fig. 7 is an elevation of the other hand-wheel, also showing part of the clutch. Fig. 8 is a plan view of the adjusting journal-box, showing the parts connecting with the pivoted guide-rod and sprocket-chain. Fig. 9 is a vertical section of part of rear end of machine, substantially on the line *z z* of Fig. 2, showing the manner of driving the small drum and also showing the drum, cable, and weights carried by the adjusting-shaft. Fig.

10 is a plan of the upper portion of one of the arms, having the yoke in which the guide-rod moves.

Similar numbers of reference are assigned 5 to corresponding parts throughout the various figures of the drawings.

In the drawings, 1 represents the frame of the winding-machine, preferably made of cast-iron in the form shown herein. 2 represents 10 a shaft driven by any suitable power and being journaled in the bearings 3, which are attached to said frame.

4 represents a large winding-drum which is carried by the shaft 2. The small drum 5 is mounted upon the shaft 6, which is journaled in the bearings 7. The shaft 6 is driven 15 by means of a belt connected with the shaft 2.

8 represents a displaceable receiving core or shaft upon which the paper is wound or rolled. 20 The core 8 is journaled in the vertically-adjustable boxes or bearings 9. These journal-boxes are made in two parts, which are joined together by means of the hinged joint 9'. The upper half of the journal-box 10 is held in a 25 closed position by means of the spring 11. The hand part 12 is provided for the purpose of opening and closing the box.

The guide-rods 13 in the present invention are preferably square in form and made of 30 steel. They are pivoted to the base of the frame at 14 by means of the pin 14'. The upper ends 13' of these guide-rods are loosely confined within the yoke or slotted aperture 18, which is formed in the upper ends of the 35 arms 16 and 16'. The aperture 18 is made large enough to permit of a slight lateral movement or vibration of the free ends 13' of the guide-rods. A cap 19 closes the open end of the yoke or aperture 18 and is secured to 40 the point of the arms by means of suitable bolts or screws. The guide-rods 13 are provided on one of their flat sides with a series of horizontal graduations or scales 13" for the purpose of indicating the diameter or weight 45 of the roll of paper. By the use of this scale the operator is able also to readily determine the size of the roll at any time and is also able to wind successive rolls of the same size. The guide-rods 13 carry the adjustable journal-boxes 9, which support the core or shaft 8, 50 upon which the paper is rolled.

In my former application referred to herein were shown and described hand-levers located at either end of machine which were 55 employed for the purpose of raising the roll of paper entirely from contact with the drums and also for holding the roll in its elevated position. By the use of these levers either end of the roll of paper could also be raised 60 separately. This feature was employed in the old device at times when the roll of paper for any reason built up or increased more rapidly at one end than the other, and by manipulating the hand-levers referred to the 65 roll could be kept substantially level through-

out the winding. In the present invention I have shown an adjusting-shaft 20, which is mounted in the journaled bearings 21, supported by the upright arms 16 and 16' of the frame, preferably in the position and in relation to the other parts of the machine, as shown in Figs. 1, 2, and 3. The adjusting-shaft 20 is not driven by power; but it is intended to be rotated wholly or partially by means of the hand-wheels 23 and 25 and also by 70 its indirect connection with the sprocket-chains located at either end of the machine, which connect with and are operated by the paper-roll during the winding of the same. The adjusting-shaft 20, as shown in detail, 80 Fig. 5, is equipped with a number of co-operative parts which adapt the same to be operated to effect a number of different adjustments producing various results. These adjustments are accomplished in the first place 85 by means of the hand-wheels 23 and 25, which have the effect of levers or cranks, mounted on the end of the shaft, which projects out beyond the upwardly-extending bracket-arms 16 of the frame. These hand-wheels are both 90 disposed concentrically with shaft 20 and are capable of being rotated by hand either separately or together by means of a feather 26 and a clutch 27, the latter being interposed between said hand-wheels. The interlocking 95 of the two hand-wheels by the aid of said clutch is maintained by means of the tension of spring 33. (Shown in Fig. 2.) The hand-wheel 23 is secured to the hollow shaft or sleeve 22, also mounted on the shaft 20 by means of a feather 24, (shown in Fig. 5,) while the hand-wheel 25 is slidable on the spline or feather 26, (shown in the same figure,) and when in engagement with said spline 100 is rotated with shaft 20. By this arrangement the wheel 25 may be pulled outwardly against the spring 33 until the clutch 27 is released, as shown in Fig. 3, and then turned to the right or left to effect the desired 105 adjustment. It will be noticed that the feather 26 does not extend beyond the hand-wheel when the latter is in engagement with the clutch 27 and wheel 23, and when hand-wheel 25 is pulled outwardly against spring 33 the full distance allowed it becomes free from the 110 feather 26 and may be turned in either direction without moving or disturbing said shaft 20 or any of the other parts thereon. The clutch 27 is composed of the male portion 29, which is cast centrally upon the face side of the hand-wheel 25, and of the female portion 28, which is similarly cast upon the back side of hand-wheel 23. These parts 28 and 29 are preferably in the form of disks, and the disk 28 is provided on its face side 115 with a series of sockets or holes 30, arranged in a circle in close order, as shown in Fig. 6. The disk 29 is provided with a series, preferably four, of dowel-pins or projecting points 31, (shown in Fig. 7,) which are ar- 120 125 130

ranged so as to engage corresponding holes 30 of disk 28, and by that means the hand-wheels 23 and 25 are interlocked and made to operate as one wheel or part. In Fig. 3 hand-wheel 25 is shown to be out of engagement with the clutch 27 and hand-wheel 23. The functions or objects of these adjustable means are as follows: In winding a fresh strip of paper upon the core or roll 8 as it comes directly from the calenders the web of the material throughout is not always of the same consistency and thickness, and therefore it is impossible to effect the even or smooth winding of the same upon the receiving-cores unless some compensating means are provided therefor. Sometimes one side is thicker or harder than the other, and at another time the same side or perhaps the center portion is harder or softer than the edges, and the rolls are often formed with sufficient unevenness or irregularity as to distort their appearance and destroy their value for commercial use. For this reason if one end of the roll of paper builds up or increases more rapidly than the other the operator will take hold of the hand-wheel 25 and pull it lengthwise of the shaft 20, so as to free it from engagement with the clutch 27. Then he will turn it either to the left or right, as the case may be, and reset the clutch in a position to effect the raising of the end of the paper-roll which requires leveling up. If the farther end of the roll requires leveling, then he will turn the hand-wheel 25 to the right the required distance and set the clutch in a new position. This operation raises the farther end of the roll of paper, but does not affect the near end of said roll. In this connection it might be well to explain that when the hand-wheel 25 is freed from the clutch, but still in engagement with the feather 26, if the said wheel is turned in either direction while held in said position it will effect the turning of the shaft 20, the pinion 43, and also spur-gear 40' and not operate the sleeve 22, the pinion 37, or the spur-gear 40; but as soon as the hand-wheel 25 is allowed to connect with wheel 23 by means of the clutch then the said shaft 20 and all of the connected parts, including both hand-wheels, will operate together, and both ends of the paper-roll will be affected in the same way. By the raising of the farther end of the paper-roll as just described a certain amount of the weight of the roll will be relieved from the winding-drum, and the paper, therefore, will not be wound as tightly on that end of the roll as on the other end, where the weight has not been so relieved. In this manner the leveling up of the roll is accomplished, and when done the hand-wheel 25 is left in the position last named until the roll is complete. If the forward end of the roll becomes out of level, the operator pulls hand-wheel 25 out of engagement with clutch 37 and holds it while an-

other workman turns hand-wheel 23 to the right a notch or more, and by that means the shaft 20 remains stationary, while the sleeve 22 and the pinion 37, keyed thereon, will be rotated thereby, and said gear being in mesh with spur-gear 40 will operate the latter, and through the sprocket-and-chain connections the weight of the roll of paper at the forward end will be relieved from the drums in the manner described. By the use of clutch 27, hand-wheels 23 and 25, and shaft 20, together with the gears, sprockets, and chains, the entire weight of the roll of paper may be lifted off the winding-drums, or any portion of said weight may be relieved during the winding of the paper on the roll, as described. The adjusting-shaft 20 will make from one to ten revolutions in winding the different-sized rolls.

A zero or level mark 44 is placed on the outer edge of each of the clutch-disks 28 29, as shown in Fig. 2. These are for the purpose of providing a gage by means of which the adjusting parts are set to bring the core or shaft upon which paper is to be wound in a true and level position. Before the paper is wound on the core the hand-wheels are set with the zero-mark 44 on each corresponding. Then the receiving-core 8 is level. After a roll has been completed and removed a new core or shaft is placed in the journal-boxes 9 and the hand-wheels and shaft 20 turned backward till the core is lowered to the starting-point between the winding-drums. Then the operator sets the hand-wheels at zero, as described, and the core is started in a true and level manner.

The spring 33 is held in place on shaft 20 by means of the collar 34, secured to said shaft by the pin or set-screw 35.

The pinion 37 and the ratchet-gear 38 are cast in one piece and are secured to the sleeve 22 by means of the key or feather 39. Being thus made rigid on said sleeve, these parts all rotate together.

40 and 40' represent the large spur-gears which are loosely mounted upon the stationary rod or shaft 41, secured to the upper ends of the arms 16 and 16'. The rod 41 in addition to carrying the large spur-gears also serves as a tie or brace to the upper parts of the frame. The gears 40 and 40' are held in position opposite to and in mesh with the pinions 37 and 43 by means of the collars 42, which are made fast to the said rod by means of suitable set-screws. The sprocket-wheels 45 and 45' are cast on the hubs of the spur-gears 40 and 40', respectively. The said gears, together with the sprocket-wheels, are revolute upon the rod 41 when driven by the pinions 37 and 43. By reason of the construction and arrangement of the adjusting parts described these gears and sprocket-wheels may be rotated either together or separately.

46 represents a sectional view of the central portions of the gears 40 and 40' and also of the sprockets 45 and 45'.

The sprocket-chains 47 and 47' are each provided with the rod or link portion 49, which is threaded throughout its length, except its upper end, which is formed into a hook 50, by means of which the said rod or link is connected with one end of the sprocket-chain. 5 The lower end of the rod 49 is fitted with the nut 51, which is attached to said rod by means of threads. A loop 52 is formed upon the nut 51 and is adapted to connect with a link of the sprocket-chain. The threaded rod or link 49 is provided with the jam-nuts 54, disposed immediately above the spring 55, and in addition to holding the spring in place also serves as means for increasing or diminishing the tension of said spring. The lower end 10 of spring 55 bears against the laterally-extended arm or lug 58 of the journal-box 9, which is slidably mounted on the guide-rod 13. The rod or link 49 passes through the hole 59 of said lug, and the nuts 60, disposed on 15 said link just beneath the lug 58, are so placed for the purpose of providing a stop for limiting the downward movement of said lug and said adjustable bearing 9, and the further object of the nuts 60 is to provide a means of 20 increasing or decreasing the tension of the spring 55, as well as to effect the raising or lowering of the bearings 9 for the purpose of adjusting the core or shaft 8 horizontally, the full purpose of these parts just referred 25 to being to afford a means of relieving or increasing the weight of the roll of paper upon the winding-drums when operated in connection with the adjustable means described and by the employment of the spring 55 to provide 30 for slight vibration of the roll during the winding of the same.

The square guide-rods 13, which support the journal-boxes 9, pass through a square aperture 61, formed in the body of said boxes, 35 as shown in Fig. 8. By this means provision is made for the sliding of said boxes upwardly and downwardly on said guide-rods. The rods 13 have a slight lateral movement or play by reason of the yoke or slotted opening 18 and the pivot 14. The axis of the paper-roll as it increases in diameter by reason 40 of the sliding of the journal-boxes on the guide-rod 13 moves upwardly in a substantially vertical course, and the lateral play of 45 the guide-rods merely provides for any vibration or oscillation of the roll of paper incident to the slight unevenness of the roll and the high rate of speed at which said roll is driven during the course of the winding. 50

55 The sprocket-wheels 62 are pivoted to the inner side of the frame at each end of the machine. These are employed for the purpose of supporting the sprocket-chains and preventing them from interfering with the 60 other working parts of the machine.

The sprocket-chains at each end of the machine are provided with the turnbuckles 63, which are employed for the purpose of adjusting the length of said chains—that is, to increase or decrease the slack or tension of 70 said chains. The turnbuckle 63 is comprised of the body portions 64 and 65. These two parts are connected by means of the screw 66, which is cast integrally with the body portion 65, the free end thereof being threaded to 75 correspond with and engage the internally-threaded part or nut 67, which is formed on the upper end of the body portion 64. 68 represents a rectangular opening through the body part 65. 69 represents a bolt or rod 80 the upper end of which is provided with the hook 70, which is adapted to connect with a link of the sprocket-chain. The bolt 69 passes through the hole 71 in the upper end of the body part 65 and extends downwardly 85 through the coiled spring 72 and the nut 73. The lower end of the bolt 69 is upset to form a head on the under side of the nut 73. The object of the said turnbuckle provided with a spring and bolt in the manner described and 90 shown is to permit of the body portion 65 being turned either to the right or to the left upon said bolt 69, as on a swivel, for the purpose of shortening or lengthening the sprocket-chain, and at the same time, by reason 95 of the employment of the spring 72 in connection with the bolt 69 and the nut 73, a certain amount of resilience or yielding tension is provided. This has been found to be necessary in order to prevent the cramping 100 or breaking of the sprocket-chain in cases where too great a tension or strain has been occasioned by the operation of the turnbuckle or from other causes.

The ratchet-wheel 38, cast with the spur-gear 37 and mounted upon the sleeve 22, is provided with the pawl 75, having the handle or lever 76 pivotally attached to the upright arm 16 by means of the bracket 77 and the pin 78. The said pawl is located so that it 110 may engage the ratchet-gear 38 and may be thrown into or out of such engagement by the operator by means of the handle 76. The object of this ratchet-gear and pawl is to enable the operator to sustain or hold the weight 115 of an extra heavy roll of paper—in other words, to prevent the recoil of the shaft 20 during the operation of the hand-wheels and related parts when adjusting or raising a heavy roll of paper.

The shaft 20 is also provided at one end with a small drum or sheave 80, as shown in Figs. 2, 3, 5, and 9, to which is attached the cable 81 and the weight 82. The said cable is adapted to be coiled or wound around said 125 drum in either direction, as shown by the full and dotted lines in Fig. 9. The object of the drum, cable, and weight referred to is to provide a suitable tension and driving power for the shaft 20 and also for the large spur-gears 130

and sprocket-wheels mounted on the stationary shaft or rod 41, the weight referred to being heavy enough to rotate the said drum and shaft 20, as well as the other connected parts. The weight 82 is also employed as a counterweight to retard the rotation of shaft 20, and therefore allow the paper-roll to bear less heavily upon the winding-drums. In case it is desired to rotate the shaft 20 toward the right the cable 81 is placed on the drum or sheave 80 in the manner shown by the full lines in Fig. 9, and when desired to rotate said shaft in the reverse direction said cable and weight are disposed as shown by the dotted lines in the same figure.

The web or canvas comprising the apron or carrier 85 is preferably about one foot in width and is endless in form, resembling a broad belt. This apron is mounted upon and carried by a series of rollers or drums, one of which, 86, acts as a driver for said apron. The other three rollers or drums 87 are merely idle carriers, disposed, preferably, as shown in Fig. 4 of the drawings, for the purpose of carrying and guiding the apron so as not to interfere with other parts of the machine. The preferred position of the apron or carrier with reference to the large drum 4 is substantially opposite the center or middle of said drum, as shown in Fig. 2 of the drawings. This has been found to be the most convenient and serviceable location for said apron, although it may at any time, if desired, be shifted toward either end of said drum and perform the same work.

88 represents the four guide rods or bars upon which the apron rollers or drums 87 are adjustably and operatively mounted. These rods or bars are secured to the base of the frame at either end of the machine, as shown by the numeral 90. Before starting to wind the paper the broad end of the strip of paper is folded or cut in the form of a V, as shown by the dotted lines 91 in Fig. 2, the point of which corresponds with the center of the apron. To begin the winding, the point 91 of the paper is inserted or fed between the apron and the drum 4 at 87' at the front of the machine, and it is then carried around to the receiving-core in a smooth and even manner. The apron or carrier 85 during the whole course of the winding is held in contact with the large drum 4, as shown in Fig. 4, under sufficient tension to keep both the said apron and the web of paper even or flat against the surface of the said drum, thereby preventing the central portion of the strip of paper from becoming wrinkled or otherwise distorted. The apron drum or roller 86 is held constantly against the winding-drum 4 under a tension strong enough to insure its being driven, and thereby cause said apron to travel at the same relative speed as the drum and the paper. In practical operation the two winding-drums 65 are driven in the same direction, (as indicated

by the arrows in Fig. 1,) and the smaller drum being of less circumferential measurement must travel at a proportionately higher rate of speed. This is accomplished by the unequal pulleys 92 93 and the belt 94. (Shown in Fig. 9.) By reason of the fact that the drums are of unequal size, as herein explained, the roll of paper, because of the position of its bearings on the pivoted guide-rod 13, will bear heaviest against the larger drum, as shown in Fig. 1, from which it will be seen that the angle of bearing with relation to the paper-roll and the large and small drums differs relatively to the respective diameters of the drums and also to the relative position of the large and small drums. The axis of the small drum, as shown by the drawings, is placed on a higher plane horizontally than the axis of the larger drum. The position of the two drums for producing the best results is preferred to be substantially as shown by the drawings.

96 represents a series of spirally-shaped grooves or recesses which are formed or cut in the surface or circumference of each of the drums 5 and 6, as shown in Fig. 2. These grooves or recesses are provided for the purpose of compensating for the rough or uneven calendering of the sheet or strip of paper. It frequently occurs that sections here and there in the length and width of the continuous strip or web of paper are of different degrees of hardness. Sometimes one edge of the strip is thicker or softer than the other, and at other times the central portion for a distance is slightly different from either of the edges. For that reason I have provided the grooves on the surfaces of the drums, and in that way as the paper passes under tension between the drums and the receiving-roll such discrepancies are in a great measure compensated for by the paper being pressed or crowded into the recesses or grooves, which take care of much of the extra fullness or unevenness in the web, and the winding continues on the roll in a comparatively smooth and even manner. The grooves are formed spirally to prevent the paper from being fluted or crimped, as would be the case if the grooves were formed straight or horizontally with the drums. The grooves or recesses are preferably placed close together, about a quarter of an inch in width by one-eighth inch in depth, to produce the best results. They are arranged on each of the drums in the same manner, and both drums travel in the same direction when in operation.

97 represents the continuous length or strip of paper as it comes from the calenders and is received by the winder and wound upon the roll 98, as shown in Fig. 1.

The hand-wheel 23 is provided with a groove 99 on its outer edge or periphery, which is adapted to receive a cable 100, to which is connected a weight or a series of detachable weights 101. This provision is made for the

same purpose as the drum 80 and cable 81 on the opposite end of shaft 20. The object in having the cable and weight at each end of said shaft is for the purpose of greater convenience in carrying out the operations of the winding-machine and also to provide additional weight, which is sometimes required in order to effect a proper adjustment of the winding parts. The cables are attached to the drum 80 and the hand-wheel 23 in such manner that either or both of them may be quickly removed (see 80') if for any reason no weights are required. The weights referred to are for the purpose also of increasing or decreasing the pressure of the roll of paper on the winding-drums. The weights may be used separately to affect the end of the roll at which they are attached and not the other end, or they may be employed to control or affect the entire shaft 20 and all the related parts.

The semicircular-shaped guard 103, having its bearings 104 on shaft 6, is provided with the projecting arms 105 and is connected with the rearwardly-extending lug 106 of the journal-box 9 by means of the link or rod 107 and the pins 108. This guard by reason of its connection with the movable journal-box 9 and its loose bearing upon the shaft 6 is operated automatically. When the receiving-core 8 is mounted in the movable boxes 9 and placed in between the winding-drums, the guard 103, by means of the said arm and link, is swung forward to within an inch or two of the said core, and then as the roll of paper increases the guard is turned backward, but always maintaining the same relative space or distance from the roll. The dotted lines at 109 represent the position of the core 8 with reference to the two drums at the start of the winding.

The stands or brackets 110, located at the rear of the machine at either end, are provided for the purpose of receiving or supporting the shaft or core 8 either before or after the paper is wound upon the same. These stands or brackets are secured to the frame in a suitable manner and for convenience are disposed as shown in Figs. 1 and 4.

111 represents a spreader for the paper, such as is commonly used in connection with paper-winding machines.

During the course of my experimenting and from actual practice with double drum-winding machines I have found that much better results are attained by the employment of drums of unequal diameter and have found that the difference in size of the drums should be relatively about two to one. Where drums of the same size are employed, a roll of paper cannot be wound with the desired evenness and much difficulty in operating and great waste of time and material have resulted from their employment. The reason for this I have found to lie chiefly in the fact that the weight of the paper-roll will bear substan-

tially evenly upon each of the two drums, and for that reason in machines where drums of equal size are employed the drums must be mounted and maintained so that their horizontal axes will be substantially on a level. It has also been found that one, preferably the first drum in the order of the winding, must be at least two feet in diameter in order to produce the best results, and if the drums are of the same size the bearing-points of the roll of paper on the two drums after the roll has increased considerably in size becomes wider apart, and this has the effect of destroying the effectiveness of the winder. Under such a construction the same amount of weight of the paper-roll will be borne by each drum, and hence it has been found impracticable to increase the speed of the second drum to the extent necessary to produce compact and even winding without tearing or distorting the paper. On the other hand, by the use of the drums of unequal size, constructed as shown and described herein, the smaller drum is preferably placed at the rear of the machine and is brought nearer to the larger drum, thereby lessening the distance between the drums and the roll of paper, which is of great advantage in drum-winding machines, and the smaller drum is also subjected to a smaller proportion of the weight of the roll of paper, because the angle of contact or bearing and the bearing-surface between the small drum and the roll is relatively only half as great as that between the large drum and the roll of paper. Hence as the weight carried by the smaller drum is so much less than that borne by the larger drum it has been found possible to provide for a slight increase in the speed of the small drum. This is accomplished by decreasing the diameter of pulley 93, mounted on shaft 6 of the smaller drum, five to ten per cent. smaller than the proportional diameter of the two drums when driven at equal surface speed. This increase of speed is fixed at such a small degree that while it exerts a slight pull on the web of the paper, just enough to keep it stretched tight on the portion of the roll already wound, there is not enough strain to cause the tearing or distorting of the material. If the winding-drums travel at the same rate of speed relatively and being kept constantly in contact with the roll of paper, which is increasing in diameter with each revolution, the layers or coils of paper after passing from the large or driven drum onto the roll apparently loosen or slacken, and it therefore became necessary to devise some means to correct or regulate this slight defect in the winding, which if allowed to continue for a number of revolutions would result in wrinkling or distorting the paper on the roll. Hence by reducing the size of the belt-pulley on the shaft which carries the small drum to the extent described it will increase the speed of said drum sufficiently to exert a slight pull

on the paper, causing the tightening of the layers of paper, and thereby effect the compact and even winding of the roll. By reason of the faster travel of the small drum there is 5 a slight constant slip of the said drum at the point where it makes the frictional contact with the paper-roll. By the use of the small drum, disposed as described, the workmen are able to get nearer to the roll of paper during the 10 progress of the winding and are thus enabled to make splices or to do any other necessary work more conveniently. One of the chief advantages derived from the use of drums of 15 unequal size arises from the fact that a larger surface or bearing contact is provided, and therefore a greater purchase is given to the roll of paper, which has been found to be necessary to properly carry out the purposes of the machine. It also allows the spool or core 20 when first starting to wind to drop down between the rolls or drums a greater distance and still be within easy reach of the operator. Under this form of construction the angle of bearing or contact is such that it affords a better 25 grip on the core or shaft upon which the paper is wound. By reason of the difference of the angle of bearing or contact referred to a larger proportion of the weight of the paper-roll is brought to bear upon the larger or 30 power-driven drum, while the smaller drum only carries such proportion of the weight as is necessary to prevent or avoid deflection of the shaft or core on which the paper is being wound.

35 It is not claimed that the double-drum feature of the present invention is entirely new to the art, as machines having a plurality of winding-drums have been in use heretofore; but it is claimed that double winding drums 40 or rolls of unequal diameter arranged and operated in the manner herein shown and described are essentially new and constitute an improvement over existing forms or makes of paper-winding devices.

45 Believing that the operation of my device will be fully understood in the foregoing, further special explanation thereof is unnecessary.

It is obvious that many of the details of the 50 construction of the device may be varied without departing from my invention.

Having thus described my invention, what I claim as new, and desire to secure by Letters Patent, is—

55 1. In a machine for winding paper, comprising two winding-drums of unequal size suitably mounted in the frame, having upwardly-extending arms secured thereto, guide bars or rods pivoted to said frame, their upward free ends being movable in yokes or slots in the upper ends of said arms, journal-boxes adjustably mounted on said guide bars or rods, a core or shaft carried by said journal-boxes, an adjusting-shaft, and means for connecting said shaft with said journal-boxes

for the purpose of raising and lowering said journal-boxes, and said core or shaft, substantially as described.

2. In a machine for winding paper, comprising a suitable frame, having bracket-arms mounted thereon, of a pair of winding-drums of unequal diameter mounted on shafts journaled in said frame, vertical guide rods or bars pivoted to said frame, their upper ends having a slight free movement in elongated slots in the ends of said bracket-arms, journal-boxes sliding on said rods or bars, a displaceable receiving-core carried by said journal-boxes, adjustable sprocket-chains to carry and operate said chains, a train of spur-gears connected with the sprocket-wheels, an adjusting-shaft in connection with said gears, and means upon said shaft for operating said gears, either simultaneously or separately to vary the winding of a roll of paper on said receiving-core, substantially as described.

3. In a machine for winding paper, comprising a suitable frame having upwardly-extending bracket-arms mounted thereon, of winding-drums of unequal diameter journaled on said frame, square guide-rods pivoted to said frame, their upper ends being laterally movable in slotted apertures in the points or ends of said bracket-arms, journal-boxes slidably mounted on said square guide-rods, a displaceable receiving core or shaft operatively supported by said journal-boxes, a sprocket-chain having a solid link or rod connecting with said journal-boxes, provided with means for adjusting said journal-boxes independently, a turnbuckle on each of said sprocket-chains adapted for adjusting the lengths of said chains, a stationary rod or shaft mounted upon said bracket-arms, a sprocket-wheel and spur-gear integrally joined, revolvably mounted on each end of said rod or shaft and adapted to be rotated separately or at the same time to effect the operation of said sprocket-chains, an adjusting-shaft journaled in said bracket-arms, pinions carried by said adjusting-shaft, in operative engagement with said spur-gears and sprocket-wheels, a sleeve or hollow shaft loosely fitted to said adjusting-shaft, to which one of said pinions is attached, a pair of hand-wheels on said adjusting-shaft, a clutch between said hand-wheels, adapting the same to be operated either separately or together, for the purpose of adjusting said journal-boxes and said receiving core or shaft, substantially as described.

4. In a machine for winding paper, the combination with a pair of winding-drums of unequal diameter, the smaller drum being constantly driven at a greater surface speed, relatively, than the larger drum, of graduated guide-bars pivoted to the frame of the machine, journal-boxes slidable on said guide-bars, a displaceable core or shaft carried by said journal-boxes, an adjusting-shaft adapted by means of a series of co-operative connect-

ing parts to raise or lower said core or shaft, a pair of hand-wheels carried by said adjusting-shaft, a clutch interposed between said hand-wheels, a coiled spring on said shaft 5 adapted to hold said hand-wheels in engagement with each other, a drum or sheave mounted on one end of said adjusting-shaft, a cable and weight detachably connected to said drum or sheave, and adapted to rotate said adjusting-shaft in either direction, and thereby to increase or decrease the weight of a roll 10 of paper upon said winding-drums, substantially as described.

5. In a machine for winding paper, the combination with the frame and a pair of winding-drums of unequal diameter journaled thereon, the smaller drum by means of belt-and-pulley connections being driven at a fixed surface speed relatively greater than that of the 15 large drum, of an endless apron or carrier adjustably disposed beneath one of said winding-drums, and being driven by frictional contact with said drum, a series of rollers or drums for supporting and driving said apron 20 or carrier, guide-rods secured to the frame upon which said rollers or drums are adjustably mounted, guide rods or bars pivoted to said frame, graduations on said rods or bars, journal-boxes sliding on said guide-bars and 25 capable of being adjusted by means of said graduations to cause the winding of successive rolls of paper of the same size or weight, substantially as described.

6. In a machine for winding paper, comprising two winding drums or rolls of unequal diameter, the small drum being driven at a 30 fixed surface speed proportionately greater than the large drum, of a displaceable receiving-core adapted to be driven by the large 35 drum and to be held in true position and partially supported by the small drum, vertically-disposed and laterally-movable guide-bars having graduations on one side or edge thereof, adjustable journal-boxes on said guide-bars to carry said core and adapted to be operated to vary the plane of said core with 40 reference to the plane of said winding-drums, an adjusting-shaft connected with said journal-boxes, adapted to be operated to increase 45 or decrease the pressure or weight of said receiving-core upon said winding-drums, and an apron driven by said large drum, adapted to carry and guide a strip of paper from the calenders to said receiving-core, substantially 50 as described.

7. In a machine for winding paper, the combination with the frame having bracket-arms mounted thereon, and a pair of winding-drums of unequal diameter journaled therein, and a 55 displaceable receiving-core, of a pair of pivoted guide-bars vertically disposed on said frame, journal-boxes slidable on said guide-bars and being adjustably connected with a pair of sprocket-chains, a turnbuckle interposed between two sections of each sprocket-

chain and adapted by means of a spring to provide a resilient adjustment for said chains, a series of sprocket-wheels to carry and drive each of said chains, a pair of spur-gears in operative connection with each of said chains, 70 an adjusting-shaft adapted to be operated to rotate said gears in directions to effect the raising or lowering of either or both ends of said receiving-core, weights disposed at each end of the adjusting-shaft, adapted for increasing or decreasing the revoluble speed or travel of said adjusting-shaft and thereby increasing or relieving the pressure of the roll of paper upon said winding-drums, substantially as described. 75

8. In a machine for winding paper, comprising two winding-drums of unequal size suitably mounted in a frame having upwardly-extending arms secured thereto, of guide bars or rods pivoted to said frame, their upper free ends 80 being movable in yokes or slots in the curved ends of said arms, journal-bearings adjustably mounted on said guide bars or rods, an adjustable shaft, and means for connecting said shaft with said journal-bearings, for the 85 purpose of raising and lowering said bearings, a displaceable core or shaft journaled in said bearings, and an endless apron carried by rollers or drums adjustably mounted on horizontal guide-rods secured to said frame, 90 one of said rollers or drums being held in contact with and driven by the large winding-drum, substantially as described.

9. In a machine for winding paper, comprising one large and one small winding-drum suitably journaled in the frame, of a detachable core adapted for winding a roll of paper thereon, vertically-adjustable bearings for said core, square guide-rods having their lowermost ends pivotally secured to said frame, 100 their uppermost ends being laterally movable, sprocket-chains connected with said adjustable bearings, a series of sprocket-gears to carry and drive said chains, spur-gears to operate said sprocket-gears, an adjusting-shaft 105 connected with one of said spur-gears, a sleeve revoluble on said adjusting-shaft and connected with a second spur-gear, a hand-wheel keyed to said sleeve and adapted to rotate therewith, a clutch member formed upon said 110 hand-wheel, a second hand-wheel slidable on said shaft and having a clutch member adapted to engage the clutch member first described, for the purpose of effecting the interlocking of said hand-wheels, a spring adapted to hold 115 said hand-wheels in locked position, a ratchet-gear and pawl adapted to prevent the recoil of the adjusting-shaft when rotated in one direction, a series of weights disposed at each end of the adjusting-shaft and adapted to assist or resist the rotation of said shaft, and an apron or carrier frictionally driven by one of said winding-drums, substantially as shown and described.

10. In a machine for winding paper of the 120

class described, comprising a pair of winding-drums of unequal diameter, of vertically-disposed guide-rods having one end pivoted to the frame, the other end having a slight lateral movement in slotted apertures in said frame, a displaceable receiving-core mounted in bearings slidable on said guide-rods, a series of adjusting means disposed at either end of said machine in connection with said receiving-core and adapted to be operated independently or together to effect the true and even winding of a roll of paper on said core, an adjusting-shaft operably connected with said adjusting means, a plurality of cables and weights attached to said adjusting-shaft and adapted to automatically rotate said adjusting-shaft in either direction, a series of hand-wheels on said adjusting-shaft, capable of being operated jointly or independently to effect the leveling of said receiving-core, and an apron adapted to carry and guide the paper, substantially as described.

11. In a machine for winding continuous lengths of paper, the combination with the winding-drums of unequal diameter driven at different surface speeds by means of belt-and-pulley connections, and a displaceable receiving-shaft mounted in bearings slidable on vertically-disposed guide-rods, of an adjusting-shaft fitted with coacting and independently-operative parts, for adjusting either end of the displaceable shaft independently of the other end, or both ends together, a series of adjusting parts connecting said receiving-shaft with said adjusting-shaft, means for operating said adjusting-shaft by hand, and means comprising weights for rotating said shaft automatically, substantially as shown and described.

12. In a machine for winding paper, comprising two winding-drums of unequal size suitably mounted in the frame, and having spirally-shaped grooves or recesses extending the full length of said drums, of upwardly-extending arms secured to said frame, square guide bars or rods pivoted to said frame, the upper free ends being movable in yokes or slots in the curved ends of said arms, journal-boxes slidably mounted on said guide bars or rods, an adjusting-shaft, means for connecting said shaft with said journal-boxes for the purpose of raising and lowering the same, a displaceable and detachable core or shaft journaled in said boxes, and an endless apron carried by rollers or drums adjustably mounted on horizontal guide-rods secured to said frame, one of said rollers or drums being held in contact with and driven by one of said winding-drums, substantially as described.

13. In a machine for winding paper of the class described, comprising a pair of winding-drums of unequal diameter having spirally-shaped grooves or recesses disposed longitudinally on said drums, of vertically-disposed

guide-rods having one end pivoted to the frame of said machine, the other end having a slight lateral movement in slotted apertures in said frame, a displaceable receiving-core mounted in bearings slidable on said guide-rods, a series of adjusting means disposed at each end of said machine connected with said receiving-core, and adapted to be operated independently or together to effect the true and even winding of a roll of paper on said core, an adjusting-shaft operatively connected with said adjusting means, a series of cables and weights connected to said adjusting-shaft, adapted to automatically rotate said adjusting-shaft in either direction, a pair of hand-wheels on said adjusting-shaft, capable of being operated jointly or independently to effect the leveling of said receiving-core, and an apron adapted to carry and guide the paper during the winding of the roll, substantially as described.

14. In a double-drum winding-machine of the class described, the combination with a pair of drums of unequal diameter, of an apron or carrier in operative engagement with one of said drums, an adjusting-shaft, a displaceable receiving core or shaft journaled in adjustable bearings, a series of mechanical connections disposed at either end of said machine and operatively connecting said adjusting-shaft with said receiving core or shaft, substantially as described.

15. In a machine for winding paper, two winding-drums, guide-bars suitably mounted and whose upper ends are free to have a lateral movement, journal-boxes vertically movable on said guide-bars, and a displaceable core or shaft carried by said boxes, substantially as described.

16. In a machine for winding paper, a pair of winding-drums, a displaceable receiving core or shaft, chains with which said core is connected, and means operatively connected with said chains for separately or in unison adjusting the opposite ends of said core, substantially as described.

17. In a machine for winding paper, a pair of winding-drums, a displaceable receiving core or shaft, chains with which said core is connected, sprocket-wheels and gears connected with said chains, suitable gears operatively connected with said first-mentioned gears, and means for actuating in unison or separately said last-mentioned gears for adjusting the ends of said core separately or in unison, substantially as described.

18. In a machine for winding paper, a pair of winding-drums, a displaceable receiving core or shaft, chains with which said core is connected, sprocket-wheels and gears connected with said chains, an adjusting-shaft, suitable gears supported by the adjusting-shaft and connected with the first-mentioned gears, and clutch mechanism for rendering

said last-mentioned gears operative, in unison or separately, for adjusting the core at one or both ends, substantially as described.

19. In a machine for winding paper, a pair of winding-drums, a displaceable receiving core or shaft, chains with which said core is connected, sprocket-wheels and gears connected with said chains, an adjusting-shaft, suitable gears supported by the adjusting-shaft and connected with the first-mentioned gears, and a clutch mechanism operatively connecting the gears on the adjusting-shaft, said mechanism comprising members capable of being disconnected from each other and having their point of connection with each other varied for adjustment, substantially as described.

20. In a machine for winding paper, a pair of winding-drums, a displaceable receiving core or shaft, chains with which said core is connected, an adjusting-shaft operatively connected with said chains to adjust said core, and a weight connected with said adjusting-shaft and shiftable from one side to the other of said shaft in rotating said shaft in either direction, substantially as described.

21. In a machine for winding paper, a pair of winding-drums, a displaceable receiving core or shaft, chains with which said core is connected, an adjusting-shaft operatively connected with said chains to adjust said core, and weights connected with said adjusting-shaft or a part thereof at each end and shiftable from one side to the other of said shaft, substantially as and for the purposes described.

22. In a machine for winding paper, a pair of winding-drums, a displaceable receiving core or shaft, chains with which said core is connected, means for actuating said chains to adjust the core, and a turnbuckle interposed between two sections of each chain for adjusting the chains, and a spring forming a part of each turnbuckle and effecting a resilient connection between the two sections of the chain united by said turnbuckle, substantially as described.

23. In a machine for winding paper, a pair of winding-drums of unequal diameter, means for driving the smaller drum at a fixed surface speed relatively greater than that of the larger drum, and a displaceable receiving core or shaft, substantially as described.

24. In a machine for winding paper, a pair of winding-drums, a displaceable receiving core or shaft, and an apron or carrier disposed opposite one of the winding-drums to coöperate therewith in feeding the paper between the winding-drums, substantially as described.

25. In a machine for winding paper, a pair of winding-drums, a displaceable receiving core or shaft, and an apron or carrier disposed opposite to one of the winding-drums and arranged relatively to one drum to be driven by frictional contact therefrom, substantially as described.

In testimony whereof I affix my signature in presence of witnesses.

JOHN J. WARREN.
